DESIGN FOR A GAS RANGE DEFLECTOR

Hercheal Wood Miller, Davenport, Iowa

Application September 6, 1941, Serial No. 103,194

Term of patent 7 years

To all whom it may concern:

Be it known that I, Hercheal Wood Miller, a citizen of the United States, residing at Davenport, county of Scott, and State of Iowa, have invented a new, original, and ornamental Design for a Gas Range Deflector, of which the following is a specification, reference being had to the accompanying drawing, forming a part thereof, in which:

Figure 1 is a rear perspective view of a gas range deflector, showing my new design;

Figure 2 is a sectional view on line 2—2 of Figure 1; and Figure 3 is a front perspective view thereof.

I claim:

The ornamental design for a gas range deflector, as shown.

H. WOOD MILLER.
